United States Patent Office

Des. 226,959

Patented May 22, 1973

226,959

FOOD MOLD

Michael J. Pasquale, 115 Grove St.,
Middletown, Conn. 06457

Filed July 21, 1971, Ser. No. 164,969

Term of patent 14 years

Int. Cl. D7—04

U.S. Cl. D44—1 L

FIG. 1 is an exploded perspective view of a food mold showing my new design;

FIG. 2 is an exploded side view thereof; and

FIG. 3 is a bottom view as seen from the bottom of FIG. 2.

I claim:

The ornamental design for a food mold, as shown.
